DESIGN FOR A DESK BOARD

Eugene M. Hoyne, Chicago, Ill.

Application October 20, 1941, Serial No. 103,822

Term of patent 7 years

To all whom it may concern:

Be it known that I, Eugene M. Hoyne, a citizen of the United States and resident of Chicago, county of Cook and State of Illinois, have invented a new, original, and ornamental Design for a Desk Board, of which the following is a specification, reference being had to the accompanying drawing, forming a part thereof, wherein appears a perspective view of a desk board, showing my new design.

I claim:

The ornamental design for a desk board, substantially as shown.

EUGENE M. HOYNE.
